FIG. 1.

FIG. 2.

FIG. 3.

FIG. 5.

FIG. 4.

FIG. 6.

FIG. 1 is a side elevation of a hip prosthesis, embodying my new design, the opposite side is a mirror image of the side shown.

FIG. 2 is an end view.

FIG. 3 is a plan view from above.

FIG. 4 is a plan view from below.

FIG. 5 is a top plan view of the socket portion of the prosthesis only.

FIG. 6 is a sectional view taken along the line VI—VI of FIG. 5.

The characteristic features of my design, reside in the specific configuration of the hip cup socket in combination with the hip joint prosthesis, as best illustrated in FIGS. 1 and 5 on the drawing.

I claim:

The ornamental design for a hip prosthesis, as shown and described.
